TIMING DEVICE

Herbert S. Beal, Ellsworth, Maine

Application May 14, 1941, Serial No. 393,361

16 Claims. (Cl. 161—15)

My present invention relates to novel timing devices or the like and comprises novel starting, stopping and dial re-setting means.

In my invention, discs or like rotatable elements are connected to the driving mechanism by clutches and are weighted so that when the clutches are disengaged, they return to a predetermined position by gravity. The disc rotating means are controlled by manually operable starting and stopping means and the clutches are under the control of manually operated releasing mechanism adapted to release a gravity operated unit after effecting the disengagement of the clutches to position and hold positively the released discs in their predetermined position until the clutches are again engaged whereafter the clutch releasing mechanism raises the unit into its inoperative position.

As the releasing mechanism has an intermediate position wherein the clutches are disengaged and the gravity operated unit is still engaged with the rotatable elements, I have provided means for holding the releasing mechanism in its intermediate position so that the same unit serves to stop the rotation of the discs automatically at the end of a predetermined interval.

While my invention may be employed with any type of disc rotating means, it is particularly well adapted for use with conventional clock mechanism, making timing devices in accordance with my invention, inexpensive to manufacture and reliable in use, so that they may serve efficiently in the many instances where the measuring of time is either convenient or necessary.

In the accompanying drawings, I have illustrated an embodiment of my invention from which its many novel features and advantages will be readily apparent. In the drawings:

Fig. 1 shows an embodiment of my invention in front view with the case partly broken away.

Fig. 2 is a side view of the device shown in Fig. 1.

Fig. 3 is a vertical section along the line 3—3 of Fig. 1.

Fig. 4 is a fragmentary rear view of the manually operated starting and stopping mechanism.

Fig. 5 shows in perspective the position of the parts when the clutches are engaged.

Fig. 6 is a view similar to Fig. 5 showing the position of the parts when the clutches are disengaged, and

Figs. 7 and 8 are views showing schematically signal operating means.

While my invention may be used with any suitable driving mechanism, I have indicated a frame 1 supporting a casing C and generally indicated conventional clockwork having a balance wheel 2 and a gear 3. The shaft 4 of the gear 3 carries a gear 5 that may be considered the driving gear for the adjustable time indicating means.

In accordance with my invention, I employ 10 manually operable starting and stopping means in control of the balance wheel 2. A bracket 6 on the frame 1 slidably supports a push rod 7 having a stop 8 engageable with the bracket 6 to limit its upward movement under the influence of the return spring 9. The lower end of 15 the push rod 7 pivotally carries a pawl 10 having a weighted end 11. A starting wheel 12 supported by the frame 1 carries pairs of pins or like members 13 and 14 disposed to be actuated by the pawl 10.

The periphery of the starting wheel 12 is recessed intermediate each of the pins 13 and 14 to receive the end of the resilient detent 15. The pins 13 are preferably resilient and are disposed 25 to engage the periphery of the balance wheel 2.

The operation of the starting and stopping means may be most readily understood by assuming a position of the starting wheel 12 wherein a pin 13 is in resilient engagement with the 30 balance wheel 2 as is shown in Fig. 3. This position may be considered the starting and stopping position since when a pin 13 is carried into or out of this position, the balance wheel 2 is stopped or started.

When a pin 12 is in the starting and stopping position, a pin 14 is in position to be contacted by the pawl 10 when the push rod 7 is depressed, while a pair of pins 12 and 13 are in an intermediate position. When the push rod 7 is de- 35 pressed, the starting wheel 12 is actuated and rotary motion is imparted to the balance wheel 2. Because the starting wheel 12 is restrained by the detent 15 and by contact of a shorter pin 14 with the push rod 7, actuation of the pawl 10

40 effects step by step rotation of the starting wheel 12. Since the pawl 10 is pivoted, the return of the push rod 7 by the spring 9 does not disturb the position of the starting wheel 12 in relation to its detent 15. The mechanism continues to 45 run with a short pin 14 in the starting and stopping position and a short pin 13 in position to be actuated by the pawl 10 when the push rod 1 is again depressed, as when the mechanism is to be stopped.

50 55 The driving gear 5 meshes with a pinion 16 on

a stub shaft 17 on which a disc 18 is mounted for independent rotation. A clutch 19 connects the disc 18 to the gear 16. The clutch is normally held engaged by pressure of the spring 20 (see Fig. 3), but may be disengaged by the throw-out lever 21. The disc 18 carries a pin or pins 22 engageable with the teeth of a gear 23 on a shaft 24 supported by the frame 1 so that the gear 23 may serve as a counter for the revolutions of the disc 18.

A clutch 25 connects a second disc 26 to the counting gear 23. The clutch 25 is normally held engaged by the spring 27 but may be disengaged by a throw-out lever 28. A resilient detent 29 carried by the frame 1 holds the gear 23 against free rotation.

The discs 18 and 26 carry weights 30 and 31, respectively, having recesses 30a and 31a, respectively, (see Fig. 6) and the weights are so disposed that when the clutches are disengaged the discs and pointers P carried thereby turn under the influence of gravity into their zero or other predetermined positions as indicated by the dials A and B on the casing C.

In order to prevent the discs 18 and 26 from remaining in a dead center position when its clutch is disengaged, I employ a spring 32 to be engaged by the pin 22 and placed under tension when the disc 18 is in its dead center position. I also employ a second pin 22a of insufficient length to engage with the gear 23 and this is so spaced that it engages with the spring 32 and acts as a brake on the rotation of the disc 18 as it approaches the zero point or other predetermined position. A pin 34 carried by the disc 26 is engageable with the spring 33 and places the spring 33 under tension when the disc 26 is in its dead center position.

In order that the clutches may be disengaged, I provide a lever 35 pivotally mounted to the frame 1 to engage with and actuate the clutch throw-out levers 21 and 28. The lever 35 includes an arm 36 disposed to be actuated by the manually operated push rod 37 normally held in its inoperative position by the spring 38. The upper end of the lever 35 is provided with a portion 39 engageable with a latch 40 holding a slide 41 supported by guides 42 in its inoperative position shown most clearly in Fig. 5. The slide 41 carries a pair of arms 43—44 having portions 43a and 44a complementary in size and shape to the recesses 30a and 31a of the weights 30 and 31.

Assuming that the timing device is stopped, the predetermined reading of the pointers P is re-established by actuating the manually operable push rod 37 to effect disengagement of the clutches and to release the slide 41 from its latch 40. The discs and pointers then rotate to their zero positions by gravity (see Figs. 5 and 6) and the portions 43a and 44a enter the recesses 30a and 31a positively positioning and holding the discs against rotation. As the push rod 37 is released to return under the influence of the spring 38, the clutches are re-engaged before the arm 37a on the rod 37 carries the slide 41 into engagement with the latch 40.

It should be noted that in the re-setting of the dials to their zero reading, there are four definite positions of the re-setting mechanism. The first of these positions finds the clutches engaged and the slide 41 held remote from the discs by the latch 43. In the second position, the clutches are disengaged while the slide 41 is still held by the latch 40, and in the third position, the latch 40 is tripped to release the slide 41 and the

clutches are disengaged. The fourth position finds the clutches engaged and the slide 41 still in its operative position wherein the portions 43a and 44a are in a position to either contact the periphery of the discs or enter their recesses 30a and 31a.

I utilize this fourth position to provide for the automatic stopping of the device at the end of a predetermined interval. I accomplish this result by employing a slide 45 engageable with the push rod 37 to hold it in the fourth position after the pointers P have been set to a desired position. The portions 43a and 44a ride on the periphery of the discs until both portions are in registry with the recesses 30a and 31a whereupon the slide 45 drops and the portions 43a and 44a become effective to stop the mechanism.

Such automatic stopping of the mechanism may be employed for many different purposes, such as the actuation of a signal of which the electric light 46 is generally indicative. The circuit 47 to the light 46 includes a pair of switches 48, 49 in series. Preferably, the switch 48 is closed whenever the slide 41 is in its low position (see Fig. 8), while the switch 49 is closed by the slide when the slide 45 is moved to retain the push rod 37 in the fourth position. As shown in Figs. 5 and 6, the switch 49 may comprise a contact 49a carried by the slide 45 engageable with the contact 49b when the slide 45 is in its operative position.

Timing devices in accordance with my invention thus provide wide adaptability with low cost, and desirable, efficient, and accurate operation.

What I therefore claim and desire to secure by Letters Patent is:

1. A timing device comprising a rotatable timing element, means to rotate said element, manually operable means to start and stop said rotating means, a normally closed clutch connecting said element to said rotating means, said element being weighted to rotate into a predetermined position by gravity when said clutch is disengaged, and second manually operable means to disengage said clutch, and gravity operated means to engage with and hold said element only when said element is in said predetermined position and said clutch is disengaged.

2. The device of claim 1 in which the holding means are also operative after said second manually operable means have been actuated to disengage said clutch and remain operative after said clutch is engaged and until said second manually operable means are in their normal position.

3. A timing device comprising a rotatable timing element, means to rotate said element, first manually operable means to start and stop said rotating means, a normally closed clutch connecting said element to said rotating means, said element being weighted to rotate into a predetermined position by gravity when said clutch is disengaged, second manually operable means to disengage said clutch, a gravity operated stop, said stop and said element having complementary surfaces, latch means normally holding said stop in such a position that said surfaces are not in engagement, and said stop being released from said latch means by said second manually operable means after said clutch is released to hold said element in its predetermined position.

4. A timing device comprising a rotatable timing element, means to rotate said element, first manually operable means to start and stop said rotating means, a normally closed clutch con-

necting said element to said rotating means, said element being weighted to rotate into a predetermined position by gravity when said clutch is disengaged, second manually operable means to disengage said clutch, a gravity operated stop, said stop and said element having complementary surfaces, latch means normally holding said stop in such a position that said surfaces are not in engagement, said stop being released from said latch means by said second manually operable means after said clutch is released to hold said element in its predetermined position, a spring to return said second manually operable means to its normal position, and means carried by said second manually operable means to return said stop into engagement with said latch after said clutch is engaged.

5. A timing device comprising a rotatable timing element, means including a gear wheel to rotate said element, and means to actuate said gear wheel to start and stop said rotating means, said starting and stopping means comprising a starting wheel, a manually operable pawl, a plurality of members carried by said starting wheel, all of said members being engageable by said pawl to effect step by step rotation of said starting wheel, alternate members being engageable with said gear wheel so that stepped rotation of said starting wheel effects the starting or stopping of said element rotating means as one of said engageable members is brought out of or into engagement with said gear wheel.

6. A timing device comprising a rotatable timing element, means including a gear wheel to rotate said element, and means controlling said gear wheel to start and stop said rotating means, said starting and stopping means comprising a starting wheel, members carried by said starting wheel to engage with said gear wheel, and manually operable means to effect step by step rotation of said starting wheel either to carry on each step an engageable member into engagement with said gear wheel to stop said element rotating means or to carry a member out of engagement with said gear wheel thereby to start said element rotating means.

7. A timing device comprising a rotatable timing element, means including a gear wheel to rotate said element, and means to actuate said gear wheel to start and stop said rotating means, said starting and stopping means comprising a starting wheel, a manually operable pawl, members carried by said starting wheel, all of said members being engageable by said pawl, detent means in control of said starting wheel whereby actuation of said pawl effects step by step rotation of said starting wheel, alternate members being engageable with said gear wheel on one step of the rotation of said starting wheel to stop said first named wheel and being movable out of engagement on a successive step to start said rotating means.

8. The device of claim 7 in which the members engageable with the gear wheel are resilient.

9. The device of claim 7 in which the manually operable pawl comprises a push rod, a pawl element pivotally carried by said rod, a spring normally urging said push rod in a position wherein said pawl element is out of contact with said members, and means positioning said pawl element for positive engagement with said members when said push rod is manually actuated against the influence of the spring.

10. A timing device comprising actuating mechanism, a rotatable timing element, a nor-

mally closed clutch connecting said element to said mechanism, gravity operated stop means, said stop means and said element having portions engageable to stop said mechanism on predetermined rotation of said element, a latch to hold said stop means remote from said element, a manually operable control for said stop means, a lever engageable by said control to disengage said clutch and trip said latch whereby said stop means moves into operative relation with said element, resilient means urging said control to carry said stop means into engagement with said latch, and means to hold said control in a position wherein said clutch is engaged and said stop means is in operative relation with said element.

11. A timing device comprising a rotatable timing element, means to rotate said element, a normally closed clutch connecting said element and said rotating means, said element having a peripheral recess, gravity operated stop means having a portion to enter said recess when in registry therewith to hold said element against rotation, a latch to hold said stop means remote from said element, a manually operable control to disengage said clutch and to release said stop means from said latch, resilient means urging said stop means into engagement with said latch, and means to hold said control in a position wherein said clutch is engaged and said stop means is in operative relation with said element.

12. A timing device comprising a rotatable timing element, means to rotate said element, a normally closed clutch connecting said element and said rotating means, said element having a peripheral recess, gravity operated stop means having a portion to enter said recess when in registry therewith to hold said element against rotation, a latch to hold said stop means remote from said element, a manually operable control to disengage said clutch and to release said stop means from said latch, resilient means urging said stop into engagement with said latch, means to hold said control in a position wherein said clutch is engaged and said stop means is in operative relation with said element, signal means, said signal means being operative only when said holding means is dominant of said control and said portion of said stop means is entrant of said recess in said element.

13. The device of claim 12 in which said signal means is electrically operated and includes a pair of switches, one of said switches being closed by said holding means and the other of said switches being closed by said stop means when said portion of said stop means is entrant of said recess in said element.

14. A timing device comprising rotating means, a first rotatable timing element, a normally engaged clutch connecting said first element to said rotating means, a second rotatable timing element, means driven by said first element to rotate said second element, a normally engaged clutch connecting said second element to said driven means, each of said elements being weighted to rotate into a predetermined position by gravity when its clutch is disengaged, a gravity operable unit, each of said elements having a recess and said gravity operable unit having a portion to enter each of said recesses, a latch normally holding said unit in an inoperative position, a lever to effect disengagement of both of said clutches and to trip said latch after said clutches are disengaged, a manually operable member to actuate said lever, a spring normally holding said manu-

ally operable member in a position wherein said clutches are engaged, return means carried by said member to return said unit into engagement with said latch when said member is actuated by said spring and after said clutches are engaged whereby said unit is effective to hold said elements after they have attained by gravity their predetermined position.

15. The device of claim 14 in which the driven means comprises an independently rotatable gear, said first element includes a portion to engage with said gear, and detent means hold said gear against rotation except when said portion engages therewith.

16. A timing device comprising a rotatable timing element, means to rotate said element, a normally closed clutch connecting said element to said rotating means, said element being weighted to rotate into a predetermined position by gravity when said clutch is disengaged, manually operable means to disengage said clutch, and gravity operable means to hold said element against rotation when said element is in a predetermined position said gravity operable means being rendered operable by said manually controlled means after said clutch has been disengaged thereby.

HERBERT S. BEAL.
